CLAIM

The ornamental design for a combined shower door shelf and planter, substantially as shown and described.

DESCRIPTION

FIG. 1 is a perspective view of a combined shower door
shelf and planter showing my new design, the bathtub
and shower doors indicated in broken lines are for illustrative purposes only;

FIG. 2 is an enlarged top plan view thereof;

FIG. 3 is an enlarged side elevational view thereof, the opposite side being identical;

FIG. 4 is an enlarged end elevational view thereof, the opposite end being identical; and

FIG. 5 is an enlarged bottom plan view thereof.
